GUN FOR FASTENER PROJECTILE

Max Skumawitz, Lintorf, Germany, assignor to Bossong-Werk G.m.b.H., Lintorf, Germany, a German firm

Application December 1, 1954, Serial No. 472,393

Claims priority, application Germany December 28, 1953

5 Claims. (Cl. 1—106)

The invention relates to a gun for impelling fastener projectiles, for use in imbedding bolts or studs or other fastening means into a solid mass, such as concrete walls or steel plates, or the like. It relates more particularly to such a gun which has a sleeve and a barrel axially shiftable relative to each other, for instance as disclosed in the patent of Carl Bossong, Patent No. 2,705,323, dated April 5, 1955.

Guns of the aforementioned type now in use, though reliable, are deficient therein that the cartridge exchange is somewhat complicated and thus requires the services of an experienced operator. Furthermore, such guns heretofore constructed are liable to give rise to hazards on those occasions when the gun is applied at an angle to the surface of the material into which the bolt is to be impelled, as the operator may be endangered by parts of the material that may be split off by the impact of the projectile.

The invention has therefore among its objects to provide a gun of this type that requires no special skill for rapid loading and ejection of the empty cartridge, and that is safe to use irrespective of the angle of the gun as applied to the material.

With the above and other objects of the invention in view, the invention consists in the novel construction, arrangement and combination of various devices, elements and parts, as set forth in the claims hereof, one embodiment of the same being illustrated in the accompanying drawing and described in the specification.

Generally speaking, this is accomplished in accordance with the invention by arranging an opening in the side of the sleeve which in certain positions of the gun parts affords manual access to the seat of the cartridge in the rear of the barrel, without any need either to disassemble the gun, or to swing the gun parts laterally as proposed in the aforementioned patent. The instant gun is furthermore provided with a safety device by which the gun is rendered incapable to be fired if the angle of attack surpasses a permissible value.

For a fuller understanding of the nature and objects of the invention, reference should be had to the following detailed description, taken in connection with the accompanying drawings, wherein

Fig. 1 is a vertical sectional view, partly in elevation, of a gun in accordance with the invention, shown in the loading position;

Fig. 2 is a fragmentary plan view, partly in section, of the same;

Fig. 3 is a large scale fragmentary plan view, partly in section, similar to Fig. 2, but showing the parts in the forward-most position subsequent to firing;

Fig. 4 is a fragmentary sectional view, similar to Fig. 1, but showing the parts in position for applying the gun against the material which is to receive the projectile;

Fig. 5 is a diagrammatic view of an arcuate cam slot illustrated, however, in rectification;

Fig. 6 is a sectional view, taken on line 6—6 of Fig. 4, showing the locking parts unlocked;

Fig. 7 is a sectional view similar to Fig. 6, but showing the locking parts locked;

Fig. 8 is a fragmentary sectional view, taken on line 8—8 of Fig. 2;

Fig. 9 is a sectional view, similar to Fig. 1, but showing the parts in firing position;

Fig. 10 is a large scale extended perspective view of the ejection mechanism of Figs. 2 and 3;

Fig. 11 is a fragmentary sectional view similar to Fig. 4, but showing the parts after the operator has pressed the gun against an object, but while the locking parts are still in the unlocked position of Fig. 6; and

Fig. 12 is a fragmentary sectional view similar to Fig. 11, but showing the locking parts in the locked position of Fig. 7, the gun being in a "ready to fire" position before the continued pressure of the operator has brought it into the "firing position" of Fig. 9.

In carrying the invention into effect in one of the embodiments which has been selected for illustration in the accompanying drawings and for description in this specification, and referring now particularly to Fig. 1, there is provided a housing generally indicated at 11, that carries on its forward end 12 in threaded engagement an apertured cover 13. To the rear end 14 of the housing 11 there is secured, for instance by screws 16, a handle 17.

A barrel assembly 18 is provided that is arranged coaxially of the housing 11. The barrel assembly 18 and the housing 11 are movable axially relative to each other. The barrel assembly 18 includes a body or body section 19, and a barrel 21 the rear end of which is in threaded engagement with the forward end of the body 19. The body 19 is arranged slidably on the internal surface of the housing 11, enabling the housing 11 to move relative to the barrel assembly 18.

An axial bore 22 is provided on the interior of the barrel 21, and forms a passageway for the projectile (not shown). Aligned with the bore 22 there is formed in the body 19 a bore 23 that forms a seat for receiving a cartridge 25 (Fig. 10).

When the gun is loaded, the cartridge 25 will be seated in the bore 23, and the projectile positioned adjacent the cartridge in the bore 22, so that upon actuation of the cartridge 25 the projectile will be expelled forwardly in direction A through, and out of, the bore 22.

The bore 23 is provided near its rear end with an enlarged portion 24 to receive the flange of the shell of the cartridge 25. An ejection mechanism is provided, generally indicated at 26, for ejecting the empty shell of the cartridge from the seat and out of the gun. This will be explained below.

The central part of the barrel 21 carries on the exterior an annular casing 27 that is threaded to the barrel 21 at 28. The casing 27 is spaced from the outer surface of the barrel 21 and defines therewith an annular gas expansion chamber 29. The casing 27 is surrounded by a circular central bore 31 of the cover 13, that serves as a journal guiding the housing 11 on the casing 27. The barrel 21 is provided with radial apertures 32 for the expulsion of expanding gases from the bore 22 into the gas expansion chamber 29.

Near the front end of the barrel 19 there is mounted externally on the casing 27 a sliding sleeve 33, that is slidable in the opposite directions A and B on the casing 27. On the sliding sleeve 33 there is secured a safety shield 34 that is movable together with the sliding sleeve 33. A dog 36 is secured to the barrel 21 and serves as a forward abutment for the safety shield 34.

A first compression spring 37 is inserted between the forward face of the body 19 and the rearward surface of the cover 13, and a second compression spring 38 operates between the frontward surface of the cover 13 and

the rearward surface of the safety shield 34. Said second spring 38 urges the safety shield 34 forwardly in direction A into abutment with the dog 36 and thereby urges the housing 11 in the direction B relative of the barrel assembly 18.

In the normal or loading position shown in Fig. 1, the two springs 37 and 38 are in balance; the housing 11 is in a rearward, though not the rearwardmost, position, relative to the barrel assembly 18.

The aforementioned ejection mechanism 26 includes an elongated sliding element 39 that is slidably arranged in a corresponding recess 41 that is formed in the external cylindrical surface of the body 19. Near its rearward end, the sliding element 39 carries an ejector 42 that has a shoulder 43. In the normal loading position shown in Fig. 2, the ejector 42 is positioned in a recess 44 that is formed in the rearward face of the body 19, and in that normal rest position the shoulder 43 is disposed forwardly of the flange of the shell of the cartridge 25 which rests in the enlarged portion 24. The sliding element 39 has a forward face 46 and an intermediate face 47. Between the faces 46 and 47 there extends a central slot 48. A tension spring 49 is connected to said intermediate face 47 of said sliding element 39 and to the front face of the body 19, and is disposed in the slot 48.

As will be explained below, the housing 11 is pushed forwardly in direction A against the power of the spring 38, prior to the firing. After the firing, and upon release by the operator, as explained further below, the spring 38 will force the housing 11 rearwardly, in the direction B.

During the said rearward movement of the housing 11 under the pressure of the spring 38, the sliding element 39 will remain at standstill with the body 19 owing to the connection thereto by the spring 49. A short distance before the housing 11 reaches the rearwardmost position (Fig. 3), however, the rear face of a flange 51 that forms part of the cover 13 will abut in the direction B against the front face 46 of the element 39. During the ensuing completion of the rearward movement of the housing 11 to the rearwardmost position of Fig. 3, the sliding element 39, owing to the abutment by the flange 51, will also move rearwardly with the housing 11. By this movement, the shoulder 43 of the ejector 42 will move the cartridge 25 rearwardly from the position of Fig. 2 to that of Fig. 3, and the cartridge will thereby be extracted rearwardly out of its emplacement in the body 19.

Following the return of the housing 11 into the normal loading position, the spring 49 will return the element 39 to its normal place to position the ejector 42 again entirely within the recess 44.

Near the rear end of the body 19 there are formed integrally therewith lugs 52.

To the rear of the body 19 there is arranged on the interior of the housing 11 a locking element or locking member 53 which is movable axially of the housing 11 and is rotatable about its axis. The locking element 53 has a central bore 54 in which there is disposed a slideable firing pin 56. The firing pin 56 and the cartridge 25 are disposed axially of the housing 11 and are aligned. The firing pin 56 has an enlarged rear flange that defines the forwardmost position of the front end of the pin 56 in which the front end projects slightly beyond the front face of the locking element 53.

Near its forward end, the locking element 53 has lugs 57 that are arranged to cooperate with the lugs 52 of the body 19 for interlocking the locking element 53 with the body 19. In the loading position (Fig. 1), the locking element 53 is spaced from the rear end of the body 19 for a distance "b".

In the housing 11 there is provided a lateral opening 58 which, in the normal position of the body 19 and of the locking element 53 (as shown in Figs. 1 and 2), is unobstructed by these parts. Accordingly, when the ejector 42 removes the cartridge 25 from its emplacement, the

cartridge 25 will automatically be discharged through the opening 58. Likewise, a new cartridge may be placed into the bore 23 by inserting it manually through the opening 58 and placing it in the bore 23.

The movement of the locking element 53 is guided by guiding means, such as a cam and a cam follower arrangement. This arrangement includes a cam slot 59 that is cut in the lateral wall of the housing 11 oppositely relative to the wall which has the opening 58. A pin 61 acts as the cam follower and is secured to the locking member 53 and extends through the slot 59 to the exterior and carries on its free end a handle 62. The positions that the handle may have are indicated in Fig. 5, and numbered with Roman numerals:

In the normal loading position (shown in Fig. 1), the handle 61 stands at I. It may be moved from that position either to the position II (shown in Fig. 11), or to the position III (shown in Fig. 12), and either of these movements results in a rotation of the locking element 53 about its axis for a fraction of a full turn. In either of the positions II (Fig. 11) and III (Fig. 12) the pin 61 may be moved longitudinally of the axis relative to the housing 11, namely from the point II to the point IV (shown in Fig. 4) forwardly for the distance "b" and, respectively, from the point III to the point V (shown in Fig. 9) rearwardly for a distance "a"; thus, the total longitudinal distance for which the element 53 may be displaced axially is the sum of "a" and "b". In order to keep the pin 61 normally in the position I, the slot 59 has near that position a restricted portion 63. By moving the pin 61 throughout the peripheral branch of the slot 59 (II-III or III-II), the locking element 53 will be rotated through an angle of 90° (Fig. 8).

In the forwardmost position IV (Fig. 4), the front face of the locking element 53 will abut against the rear face of the body 19 in the loading position thereof, but the lugs 57 are so disposed in the position IV (as shown in Fig. 6) that there is no interlocking of the lugs 57 with the lugs 52.

To the rear of the locking element 53 there is disposed in the housing 11 a backing member 64 that is secured against axial movement by means of a holding element such as a split ring 66.

The locking element 53 is hollow to the rear, and carries a plate 67 that has an aperture 68. The aperture 68 is smaller than the rear flange of the firing pin 56, and is in alignment therewith to the rear thereof. The plate 67 thus prevents a rearward accidental removal of the firing pin 56 from the bore 54.

A compression spring 69 extends between the front side of the backing member 64 and the rear side of the plate 67, and presses the plate 67 into its seat, and at the same time urges the locking member 53 forwardly, tending to move it in direction A when the pin 61 is either in the branch III-V or in the branch II-IV of the slot 59.

The backing member 64 has a central bore 71 which is in axial alignment with the aperture 68 of the plate 67, and through which there extends the forward portion of a firing bolt 72. The rearward portion of the firing bolt

72 extends through a bore 73 of the handle 17, and has an upright grip 74 for manual operation. As may be clearly seen in Figs. 1 and 9 of the drawings, the cross section diameter of bolt 72 is smaller than those of bores 71 and 73. Clearance is thereby provided between the bolt and the bores, permitting radial as well as axial movement, so that firing bolt 72 can be flexed when grip 74 is lifted. The bolt 72 has on the opposite side of the grip 74 a recess 76, which cooperates with a locking pin 77 for holding the bolt 72 in cocked position (Fig. 1). The

grip 74 is disposed in a slot 78 that is formed in the upper side of the handle 17 to permit the cocking and firing movement in directions B and A, respectively, of the bolt 72. A spring 79 presses against a flange 81 that is formed on the bolt 72, to urge the bolt forwardly in direction A. The firing stroke of the bolt 72 is limited by the abutment

between the flange 81 and a rear surface 82 that is formed adjacent the bore 71 on the backing member 64.

The operation of the gun described in the foregoing is as follows:

The loading is carried out in the loading position (Fig. 1), wherein the pin 61 is disposed at the point I of the slot 59 and the housing 11 is relative to the barrel assembly 18 in a rearward position defined by the equilibrium of forces of the springs 37 and 38. In this loading position, the opening 58 is unobstructed, and a cartridge may be emplaced in the bore 23. Likewise, the projectile is inserted into the bore 22, for instance through the front end of the barrel 21, into a position adjacent the cartridge. The firing bolt 72 will be moved by the operator into the cocked position as shown in Fig. 1 against the force of the spring 79. Subsequently, the operator will turn the pin 61 from the position I into the position II (Fig. 11), by which movement the locking element 53 is rotated about its axis for a small angle, and thereafter the spring 69 will shift the pin 61 from the position II (Fig. 11) to the position IV (Figs. 4 and 6), by moving the locking element 53 forwardly into abutment with the body 19 without interlocking.

Then the operator will apply the gun to the material 83 into which the projectile is to be imbedded, for instance concrete or the like. The operator holding the handle 17 will apply the safety shield 34 against the material 83, and exert manual pressure on the handle 17 in the direction A towards the material 83. The housing 11 will thereby be pressed forwardly in direction A relative to the barrel assembly 18, and relative to the locking member 53 which abuts against the body 19. By this movement of the housing 11, the cam slot 59 will move relative to the pin 61 throughout the distance "b" until it engages the pin 61 at point II (Fig. 11). In this position II there exists no possibility of any accidental firing, as the firing pin is out of striking reach of the bolt 72; the bolt 72 can strike the firing pin 56 only after the housing 11 has been pushed forwardly relative to the barrel assembly 18 and the locking element 53 abutting thereon for the additional distance "a."

Thereafter, the operator will turn the locking member 53 from the position II (Figs. 6, 11) to the position III (Figs. 7, 12). By this rotation, the lugs 57 have been moved from the unlocked position (Fig. 6), to the locked position (Fig. 7), interlocking the element 53 with the body 19. By this locking rotation to the position III, the pin 61 has been put in position to enable a further forward movement of the housing 11 relative to the barrel assembly 18 and the locking element 53 latched thereto as guided by the branch III—V of the slot 59. The operator will continue to exert the pressure against the handle 17 in the direction A towards the material 83, and the housing 11 will move forwardly, with the slot 59 moving relative to the pin 61 so that the engagement of the pin will be changed from III to V after the movement has covered the distance "a." In this position V (Fig. 9) the firing pin 56 has been brought within the striking range of the bolt 72.

By manually lifting the grip 74, the firing bolt 72 will be disengaged from the locking pin 77 and is ready for forward movement, and the spring 79 will press the bolt 72 forwardly to strike the pin 56 which, in turn, will strike the cartridge 25 to expel the projectile through the bore 22 into the material 83.

After the projectile has been fired, the operator will relax the pressure on the handle 17, and the combined force of the springs 38 and 69 will push the barrel assembly 18 forwardly relative to the housing 11. During this forward movement, the pin 59 will shift between the positions V (Fig. 9) and III (Fig. 12) of engagement with the slot 59. Subsequently after the gun has been moved off the material 83, the operator will rotate the locking element 53 by moving the pin 61 from the point III (Fig. 12) to the point II (Fig. 11), thereby

unlocking the lugs 57 from the lugs 52. Owing to inertia, the barrel assembly 18 will move forwardly beyond the loading position (Fig. 1) into the forwardmost position (Fig. 3). As explained earlier herein, during this phase, the cartridge will be lifted by the ejector 42 off its seat, and be expelled through the opening 58. Subsequently, the opposing forces of the springs 37 and 38 will again be balanced, returning the barrel 18 relative to the housing 11 into the loading position (Fig. 1), and by this return movement the ejector 42 will assume its position in the recess 44 (Fig. 2).

In order to avoid that the sliding piece 39 of the ejector 42 during its repeated opposite movements along the internal surface of the housing 11 may work any damage to that surface, there is provided a set screw 84 that has on the interior of the housing 11 a rounded surface 86. The screw 84 is adjustably secured by a nut 87. During the movement in direction A between the positions V and III, of the barrel assembly 18 relative to the housing 11, immediately after the firing of a shot, the sliding piece 39 of the ejector will be prevented by the screw 84 from rubbing against the interior surface of the housing 11.

The sliding sleeve 33 may be pressed rearwardly for a total distance "s" (Fig. 1), as the rear face of the sleeve 33 abuts in its rearmost position against a front flange 88 that is formed on the cover 13. The distance "s" is so chosen, that the outer sleeve 33 can cover it only when the axis of the barrel 21 is approximately perpendicular to the surface of the material 83. As best shown in Fig. 1, the distance "s" is only slightly larger than the sum of the distances "a" and "b" for which the housing 11 must be moved forwardly in order to render possible the firing of the projectile. Therefore, if the barrel 18 is not perpendicular to the surface of the material 83, there will, before pressure is applied, appear a distance "d" between the front of the barrel 18 and the point of entry of the projectile into the material 83. If the distance "d" surpasses the value of the difference between the distance "s" and the sum of the distances "a" and "b," firing becomes impossible as the housing 11 can no longer be pushed forwardly for a distance sufficient to bring the bolt 72 within the range of the firing pin 56.

By this arrangement, it is assured that only a small digression from the proper shooting direction is possible. The operator is thus safeguarded against splinter action of the type that would occur were the gun positioned beyond that permitted digression.

I wish it to be understood that I do not desire to be limited to the exact details of construction shown and described, for obvious modifications will occur to a person skilled in the art.

Having thus described the invention, what I claim as new and desire to be secured by Letters Patent, is as follows:

1. In a gun adapted to drive a fastening device into a solid mass, in combination, a barrel for said fastening device, said barrel including a rear end portion having a seat for a cartridge, a housing surrounding said rear end portion and being movable axially relative to said barrel, a locking member movably disposed in said housing and normally being spaced from the rear end of said barrel and being movable and rotatable for closing releasably said rear end, and firing means operatively positioned to detonate said cartridge, said housing having an opening adjacent the normal position of said locking member affording manual access to said seat, said housing having a cam slot, said locking member including a pin projecting through said cam slot to the exterior of said housing for manual application, said cam slot having a section extending for a portion peripherally of said housing and sections at the ends of said peripheral section extending parallel to the housing axis, whereby said locking member may be moved in either axial direc-

tion first axially, then rotated for locking and unlocking respectively with said barrel, and then be moved axially again.

2. In a gun adapted to drive a fastening device into a solid mass, in combination, a barrel for said fastening device, said barrel including a rear end portion having a seat for a cartridge, a housing surrounding said rear end portion and being movable axially relative to said barrel, a locking member movably disposed in said housing and normally being spaced from the rear end of said barrel and being movable and rotatable for closing releasably said rear end, and firing means operatively positioned to detonate said cartridge, said housing having an opening adjacent the normal position of said locking member affording manual access to said seat, together with a spring urging said locking member forwardly relative to said housing.

3. In a gun, employing an explosive cartridge device to drive a fastener into a solid mass and provided with a handle and a backing member formed with co-axial bores, the combination of a barrel assembly for said fastener, a housing assembly axially movable relative to said barrel between protracted and contracted positions, resilient means between said assemblies maintaining them in the protracted position, said barrel assembly including a seat for receiving said explosive device, said housing assembly having an opening affording manual access to said seat in said protracted position, a locking element axially movable in the interior of said housing assembly and operable to be releasably latched to the rear end portion of said barrel assembly and when unlatched to block said barrel assembly and housing assembly from reaching said contracted position, and when latched to said barrel to guide said barrel assembly and housing assembly to the contracted position upon the exercise of manual pressure exerted upon said housing assembly while said barrel assembly is applied to a solid mass for firing, and

10 ejecting means for ejecting through said opening the cartridge of said explosive device following the firing, said opening being positioned adjacent said seat, said locking element being axially movable and axially rotatable within said housing assembly, said housing assembly having a substantially Z-shaped slot, a pin connected to said locking element and extending through said slot, said locking element being movable by manual movement of said pin, said ejecting means being slidably arranged in said barrel assembly near the rear end thereof.

15 4. In a gun as claimed in claim 3, said locking element having an apertured plate, a firing pin, a spring pressing said plate of said locking element to secure said firing pin from accidental dislodging, and a spring powered firing bolt extendable through the aperture of said plate.

20 5. In a gun as claimed in claim 3, a firing bolt having a cross-section smaller than those of the co-axial handle and backing member bores, said bolt being movable in said bores axially and having radial motion play therein permitting it to be flexed, and being settable to a rearwardmost position, said firing bolt having a recess, a pin mounted in said housing assembly engaging said recess in the rearwardmost position, said firing bolt being releasable from said pin by movement at right angle to the 25 axis of said bores.
